by *Alfred, Dan*
His Attorney

UNITED STATES PATENT OFFICE.

TERRY T. KING, OF FORT WAYNE, INDIANA, ASSIGNOR TO GENERAL ELECTRIC COMPANY, A CORPORATION OF NEW YORK.

ELECTROMAGNETIC DEVICE.

1,315,777.

Specification of Letters Patent. Patented Sept. 9, 1919.

Application filed November 2, 1915. Serial No. 59,218.

To all whom it may concern:

Be it known that I, TERRY T. KING, a citizen of the United States, residing at Fort Wayne, in the county of Allen, State of Indiana, have invented certain new and useful Improvements in Electromagnetic Devices, of which the following is a specification.

My invention relates to electromagnetic devices, and has for its object the provision of a device of this character which is simple in construction and reliable and efficient in operation.

In its broadest aspect, my invention comprises an electromagnetic device having a plurality of separate magnetic paths, with means tending to simultaneously induce therein a magnetic flux change, and means for normally restraining said change in all the magnetic paths but one.

It will be apparent that my invention may take a variety of forms. For example, in the particular embodiment of my invention illustrated in the drawings I have shown the electromagnetic device adapted for controlling electric circuits, and in the form illustrated this is accomplished by providing a member which is movable in response to flux changes in the respective magnetic paths.

For a fuller understanding of my invention, reference may be had to the accompanying drawings, in which Figure 1 is a diagrammatic view, including the circuit connections, of a device embodying my invention; Fig. 2 is a front elevation; and Fig. 3 is a side view.

Referring, now, to the drawings in which I have shown one embodiment of my invention, A is a base plate on which the device is mounted. The primary coil 10 of a transformer is connected to the supply conductors 11 and 12 of an alternating current circuit, in connection with which my invention is particularly applicable, although it will, of course, be understood that the same can be used with a pulsating unidirectional current. This coil is wound upon the central portion 13 of an E-shaped core B. The primary coil sets up a magnetic flux which divides and passes through two paths formed by the two outer legs 14 and 15 of the core and an armature 16 which is pivoted at 17 on the core. The armature is

designed to oscillate, sufficiently to operate 55 switch contacts, between one or the other of the legs 14 or 15 of the core and the adjacent end of the armature. The outer ends of the legs 14 and 15 and the adjacent ends of the armature 16 are preferably wedge-shaped, as shown, and the portion of the armature which co-operates with the middle leg 13 is preferably made with a semi-circular fit so that the air gap on the middle leg is constant, irrespective of the position of 60 the armature. This has the effect of practically eliminating vibration or chattering at the contacting parts when the device is used on alternating current. Secondary coils 19 and 20 are wound upon the legs 70 14 and 15, respectively, of the core. The circuits for these coils are controlled by a switch C, which I have here shown as comprising a helical thermostat, but which may in practice be any form of switch, and may, 75 if desired, be manually operated. The outer end of the thermostat 21 is attached to a pivoted arm 22, the free end of which engages contacts 23 and 24, preferably by a snap action. The contact 23 is connected 80 to one terminal of the coil 19, and the contact 24 to one terminal of the coil 20, by conductors 25 and 26, respectively, while the other terminals of these two coils are connected by conductors 27 and 28 to the 85 thermostat. It will thus be apparent that when the end of the arm 22 is in engagement with the contact 23, the coil 19 is included in a closed circuit, and when it is in engagement with the contact 24, the coil 20 is similarly included in a closed circuit. A working circuit is controlled by the movement of the armature 16 through movable contacts 29 which engage stationary contacts 30. The contacts 29 are mounted on flexible arms 31, carried by elbow levers 32, and pivoted at 33 to brackets mounted on the base A. The levers 32 are actuated by means of arms 34, the upper ends of which are pivoted to the levers 32 at 35, and the lower ends of 90 which are pivoted to a cross-bar 36 secured to the upper end of the armature 16. The links 34 thus constitute, with the armature 16, a toggle, which, when straightened, 95 causes the levers 32 to move anti-clockwise, as viewed in Fig. 3, and the contacts 30 to engage the contacts 29. The armature and the parts connected thereto are so arranged 100 105

that normally the contacts 29 will move outwardly away from the contacts 30.

The operation of the device embodying my invention is as follows: When a circuit 5 is closed to the primary coil 10 from the supply conductors 11 and 12, a magnetic flux is set up which passes through the two branches formed by the legs 14 and 15 of the core and the armature, and the relative 10 amounts of flux in the two branches are inversely proportional to the relative reluctance of the two paths, the larger amount of flux passing through that path which has the shorter air gap, with the result that the 15 armature will be attracted to and held tightly by one end, so that one magnetic path will have practically no air gap and a minimum magnetic reluctance, and the other a substantial air gap,—for example, one- 20 quarter of an inch, and a relatively large reluctance. The preponderance of flux in one path over that in the other will, therefore, hold the armature 16 firmly in a given position. Now, the flux passing through 25 the two magnetic circuits sets up a voltage in the secondary coils 19 and 20 proportional to the number of turns and the amount of flux. Assume, now, that the working circuit is open and the armature in the position shown, and that it is desired to move 30 the armature to the other position and close the working circuit. If, for example, my invention is used in the manufacture of ice, or in refrigeration, the conditions may re- 35 quire that the circuit to a motor be closed, and this condition will be brought about by such a change in temperature as will bring the arm 22 into engagement with the contact 24. This closes a circuit through the 40 coil 20, and a current will be set up in the coil, which, in turn, sets up a magnetic flux which is superimposed upon the flux due to the primary exciting coil 10. This flux, which opposes the main flux, weakens the 45 pull exerted on the armature 16 between the end of the leg 15 and the adjacent end of the armature, with the result that the attraction exerted at the other end of the armature will overpower that exerted at the end 50 adjacent the leg 15, and the armature will be tilted to bring the end of the armature into engagement with the leg 14. During this tilting movement, the increase in air gap at the left in Fig. 1 will still further 55 weaken the attraction exerted by the leg 15 on the adjacent end of the armature by weakening the flux in that branch of the magnetic circuit, while the decrease in air gap between the leg 14 and the adjacent end 60 of the armature will correspondingly increase the attraction exerted on that end of the armature, so that, once started, the armature moves quickly into its new position.

In the same manner, when the arm 22 is 65 caused to engage the contact 23, the coil 19

is included in a closed circuit, and the armature is caused to move back into the position shown in Fig. 1.

It is an important feature of my invention that the circuits of the secondary coils 70 are broken at the thermostat when the current and voltage at the contacts are practically negligible. This is because the change in the position of the armature takes place before the circuit is broken at the contacts. 75 When the armature is moved from the position shown in Fig. 1, for example, in which case the coil 20 is short-circuited, the movement of the armature takes place before the arm 22 leaves the contact 23, so that an air 80 gap is introduced into the magnetic path of the coil 20, which serves to cut down the voltage and the current in this coil, so that when the circuit is broken at the contacts of the thermostat, no sparking in practice 85 takes place.

In accordance with the provisions of the patent statutes, I have described the principle of operation of my invention, together with the apparatus which I now consider to 90 represent the best embodiment thereof; but I desire to have it understood that the apparatus shown is only illustrative and that the invention can be carried out by other means. 95

What I claim as new and desire to secure by Letters Patent of the United States, is:

1. An electromagnetic device, comprising a movable member having two positions, an operating winding having two magnetic circuits, a source of alternating current connected to said winding for setting up a variable flux in the respective magnetic circuits, and a winding associated with each magnetic circuit and energized at will to superimpose magnetization upon either magnetic circuit and cause the other magnetic circuit to predominate and move the member. 100

2. An electromagnetic device for alternating current circuits, comprising a movable member having two positions, an operating winding having two magnetic circuits, a source of alternating current connected to said winding for setting up a variable flux in the respective magnetic circuits, a winding associated with each magnetic circuit and inductively related to the operating winding for superimposing magnetization thereon, and means for closing the circuit of either winding to cause one of the magnetic circuits to predominate and move the member. 115

3. An electromagnetic device for alternating current circuits, comprising a movable member having two positions, an operating winding having two magnetic circuits, a source of alternating current connected to said winding for setting up a variable flux in the respective magnetic circuits, a winding associated with each magnetic circuit to 120

oppose the flux of the operating winding, and means for energizing either winding to cause the other magnetic circuit to predominate and move the member.

5. 4. An electromagnetic device for alternating current circuits, comprising a movable member having two positions, an operating winding having two magnetic circuits, a source of alternating current connected to 10 said winding for setting up a variable flux in the respective magnetic circuits, a winding associated with each magnetic circuit and inductively related to the operating winding to oppose the flux of the operating 15 winding, and means for energizing either winding to cause the other magnetic circuit to predominate and move the member.

5. In a circuit controller, a magnetizing winding, a branched magnetic circuit there- 20 for comprising a movable armature for controlling a circuit, means comprising secondary windings inductively related to the respective branches of said magnetic circuit for varying the relative amounts of flux in 25 the two branches of said circuit, and means for including either of said secondary wind- ings in a closed circuit.

6. In a controller, an E-shaped core pro- 30 vided with a magnetizing winding on its middle leg and having a branched magnetic path through the other legs, a coöperating pivoted armature, an auxiliary winding on each of the outer legs, and means for in- 35 cluding either of the latter windings in a closed circuit.

7. An electromagnetic device comprising a primary winding, a plurality of magnetic circuits therefor, a choke coil surrounding each magnetic circuit and means for ren- 40 dering said choke coils alternately effective.

8. An electromagnetic device comprising a core forming a plurality of magnetic circuits, a winding for setting up a variable flux in each of said circuits, means associated 45 with each circuit for setting up a flux there- in opposing the flux due to the winding, means for varying the relative amounts of

the opposing fluxes, and a circuit controlled by the variations in the relative amounts of said opposing fluxes. 50

9. An electromagnetic device comprising a core forming a plurality of magnetic circuits, a winding for setting up a variable flux in each of said circuits, means associated with each circuit for setting up a flux 55 therein opposing the flux due to the winding, means for varying the relative amounts of the opposing fluxes, and a member movable in response to the variations in the relative amounts of the opposing fluxes. 60

10. An electromagnetic device comprising a core forming a plurality of magnetic circuits, a winding for setting up a variable flux in each of said circuits, means associated with each circuit for setting up a flux 65 therein opposing the flux due to the winding, means for varying the relative amounts of the opposing fluxes, an armature forming a part of said magnetic circuits and movable in response to the variations in the 70 relative amounts of the opposing fluxes, and a circuit controlled by the movement of said armature.

11. In a circuit controller, a core member, 75 a winding for setting up in said core mem- ber two magnetic circuits, means for alter- nately choking back the flux in the respec- tive magnetic circuits, and a movable mem- ber responsive to the flux changes in said magnetic circuits for controlling an electric 80 circuit.

12. In a circuit controller, a core member, 85 a winding for setting up in said core mem- ber two magnetic circuits, two damping coils associated with the respective magnetic cir- cuits, means for alternately closing the cir- cuits of the damping coils, and a movable member responsive to the flux changes of the respective magnetic circuits for control- 90 ling an electric circuit.

In witness whereof I have hereunto set my hand this 30th day of October, 1915.

TERRY T. KING.
